METHOD OF CHARGING AND CONDITION-
ING DEHYDRATORS

Guy J. Henry, Chicago, Ill.

Application June 4, 1938, Serial No. 211,849

7 Claims. (Cl. 210—134)

The present invention relates to an improved method of charging, drying and sealing dehydrators and refers in particular to the packing of a dehydrator with granular dehydrating material in such a manner as to assure the user of full utility of the apparatus.

A principal object of the invention is the packing of a dehydrator with a granular dehydrating substance by a method which involves the combined use of vacuum and pressure.

An additional object of the invention is to provide a method for charging dehydrators and conditioning the same for use by the vacuum treatment followed by subjecting the dehydrating agent to dehydrated air under pressure and sealing the dehydrator to maintain the pressure condition until the dehydrator is ready for use, the pressure condition being made evident by the provision of means for indicating the escape of air at the time when the dehydrator is being installed for use.

A still further object is the provision of a dehydrator having a body portion provided with an internally extending porous distributing element surrounded by the granular dehydrating agent and the latter being maintained under superatmospheric pressure before use, the distributing element being provided with means for allowing escape of the air within the dehydrator through the distributing element before the dehydrator is used.

These and other objects will be observed upon a consideration of the following description of a preferred embodiment of the invention and by reference to the accompanying drawing, in which the single figure is a longitudinal sectional view of a dehydrator constructed, charged, dried and sealed in accordance with the invention.

The dehydrator shown in the drawing includes a cylindrical casing 10 constituting a fluid treating chamber and having a closed inlet end 11 provided with an orificed inlet connection 12. Connection 12 may be secured to the casing by welding, soldering or in any other suitable manner to provide an air-tight or fluid-tight seal.

The inlet connection 12 has a cylindrical flange 13 extending through the end of the cylinder and inwardly thereof. Connected with the extension 13 is a longitudinally extending fluid distribution member 14 which consists of a porous metallic cylinder of substantially less diameter than the diameter of the treating chamber and having perforations of somewhat smaller size than the particles of the treating agent which is loaded in the cylinder. The end of the distribution member 14 is provided with a closure 15.

The opposite end of the cylinder 10 from the closed end 11 is provided with a separate closure cap 16. The closure cap 16 has an internal flange 17 and a spaced external flange 18 which

5 fit over the open end of the casing 10. After the various elements of the dehydrator are assembled the cap portion 16 may be sealed to the casing in any suitable manner such as by soldering the flange 18 to the casing wall.

The central part of the casing head 16 is provided with an orificed outlet member 19 which is soldered or welded in position in an opening through the casing head, as indicated in the 10 drawing. The outer portion of the outlet member 19 is provided with a threaded closure cap 20 having a gas-tight seat 21 fitting against the end of the outlet member.

The inlet connection 12 also is provided with a threaded closure cap indicated at 22, this cap being similar to cap 20 except that it is provided with gas escape opening 23 which is spaced from the seat 21 sufficiently to prevent escape of gas from the dehydrator while the seat 21 is fitted against the end of the inlet opening 24. Opening 23 also is positioned so as to allow escape of gas from the dehydrator when the cap is unscrewed. The construction of the cap and opening is such that when the casing 10 is held under superatmospheric pressure and cap 22 is loosened from closed position, there will be a distinct sound caused by escape of air through the orifice 23.

25 Internally of the casing 10 adjacent the outlet member 19 is a screen 25. This screen is held in position in the casing by a split ring 26 and rests against a shoulder provided by the casing cap 16. Internally of the ring 26 is a spring 27 which presses inwardly against a second coarse screen or retention member 28, the latter being held 30 against a felt or metallic wool pad 29 which bears against the body 30 of dehydrating material contained in the casing, thereby maintaining the dehydrating agent in compact condition.

35 In accordance with my improved loading method the casing 10 initially is provided with the inlet member 12 and internally extending distribution member 14. The casing then is loaded with a granular dehydrating agent such as activated alumina, calcium chloride, or silica gel. These dehydrating agents are examples of the many substances which may be used in the apparatus. During the loading operation the casing 10 is subjected to a vibration which insures that the particles of the dehydrating agent are loaded in compact relation. The vibratory movement also causes the particles of the dehydrating agent to brace against each other to retard any tendency for the particles to shift in their position after the loading operation is complete. Granular materials of this nature many times 40 will shift their position after being placed in a container so as to reduce the uniformity of the distribution of the material. In particular, the dehydrating agent 30 is packed with care about

the longitudinally extending distributional member 14. The size of the particles and the nature of the packing operation are such that compactness is obtained without blocking the perforations or openings in the distributional member 14 and without closing the tortuous passages between the particles of the dehydrating agent.

After the dehydrating agent is packed properly the retention member 28 and pad 29 are placed in position and spring 27, ring 26 and retention member 25 likewise are assembled by the operator. Thereafter the cap 16 is placed in position and sealed to the casing to complete the assembly operation. The tension of spring 27 maintains the compactness of the dehydrating agent after the loading operation.

After the particles of dehydrating agent have been packed in the casing and the head 16 has been assembled, air under pressure is blown through the dehydrator from the outlet connection 19. This air picks up dust particles produced in the packing operation and removes them through the inlet connection, this removal being facilitated by the absence of a pad similar to pad 28 at the inlet end.

The dehydrator assembled as described then is placed in a vacuum oven for conditioning. The reduced pressure and heat conditions the particles of dehydrating agent to insure the full and expected use of the dehydrator. The extent of the vacuum and heat and the time during which the dehydrator is subjected to the reduced pressure and heat may vary widely, as will be understood.

After completion of the vacuum oven treatment for conditioning the dehydrating agent, the seal cap 28 on the outlet end of the dehydrator is turned into closed position and the particles of dehydrating agent are subjected to the action of dehydrated air under superatmospheric pressure, as by passing such air through opening 23 in cap 22 while the latter is only partially screwed down on the inlet connection. Replacement of the vacuum by the dehydrated air pressure further conditions the particles of dehydrating agent, and in accordance with my improved method the casing 10 is closed while the particles are maintained under superatmospheric pressure. Cap 22 is tightened while the air pressure still is on. This causes the particles of dehydrating agent to be maintained under superatmospheric pressure until the dehydrator is ready for use.

When it is desired to couple the dehydrator into a fluid system in which it is to act in its normal capacity, the cap 22 adjacent the inlet connections initially is removed. As the cap is unscrewed the air under pressure in the dehydrating agent is allowed to escape so that when the dehydrator is coupled in the system it is under normal pressure. The escape of the air from the casing 10 causes a distinct sound as it passes through the opening 23, thereby assuring the user the dehydrator is in good condition and ready for use. The packing operation and handling of the dehydrator before its period of use tends to cause the formation of more or less powder from the granular dehydrating agent. By initially opening the cap on the inlet member to which the distributing element 14 is attached, this powder is incorporated in the escaping air and thereby removed from the casing so that it can not enter the fluid system in which the dehydrator is used.

Many changes from the invention as described herein for the purpose of explanation may be made without departing from the scope thereof as defined in the appended claims.

I claim:

1. The method of preparing a dehydrator for use, which comprises loading a dehydrator casing with granular dehydrating material, subjecting the dehydrating material to the action of a vacuum after being loaded into the dehydrator casing, following the vacuum treatment by subjecting the dehydrating material to the action of air under pressure, and closing the casing to entrap the air under superatmospheric pressure and to maintain the dehydrating material under such condition before use.

2. The method of preparing a dehydrator for use, which comprises loading a dehydrator having an internally extending distribution member with a granular dehydrating agent, subjecting the casing to a vibratory movement to compact the granular dehydrating agent about said distributional member, closing the casing, subjecting the dehydrating material in the casing to a vacuum, following the vacuum treatment by subjecting the dehydrating material to the action of dehydrated air under pressure, and sealing the dehydrating material under pressure.

3. The method of preparing a dehydrator for

use, which comprises loading an open-ended dehydrator casing with granular dehydrating material, subjecting the dehydrating material to vibratory packing, assembling the casing with a closure, blowing air under pressure through the casing to remove dust, subjecting the loaded dehydrating material to the action of heat and reduced pressure, following said last named treatment by subjecting the dehydrating material to the action of dehydrated air under superatmospheric pressure, and closing the casing while the dehydrating material is being subjected to the air under pressure.

4. In the conditioning of a dehydrator filled with granular dehydrating agent, the steps which comprise consecutively blowing air through said dehydrating agent under pressure, subjecting said agent to heat and reduced pressure, and sealing said agent in an atmosphere of compressed dehydrated air.

5. In the conditioning of a dehydrator, the steps which comprise loading a dehydrator casing with a granular dehydrating material, subjecting the dehydrating material in said casing to action of air under superatmospheric pressure, and closing the casing while the dehydrating material is under said pressure.

6. A dehydrator of the type described, comprising a casing, an internally extending distributional member, said casing being packed with a granular dehydrating agent about said distributional member, inlet and outlet connections on said casing, an orificed closure member for said inlet connection, and means for sealing the closure member, said dehydrating agent being maintained in the casing under superatmospheric pressure.

7. A dehydrator of the type described, comprising a casing packed with granular dehydrating agent, inlet and outlet connections on said casing, an orificed closure member for said inlet connection, and means for sealing said casing under superatmospheric pressure.

GUY J. HENRY.
